UNITED STATES PATENT OFFICE.

MARC BIRKIGT, OF BOIS-COLOMBES, FRANCE.

CARBURETER.

1,205,846.

Specification of Letters Patent. Patented Nov. 21, 1916.

Application filed January 8, 1916. Serial No. 71,083.

To all whom it may concern:

Be it known that I, MARC BIRKIGT, citizen of the Republic of Switzerland, residing at Bois-Colombes, Department of Seine, France, have invented certain new and useful Improvements in Carbureters, of which the following is a specification.

This invention relates to carbureters, particularly to multiple carbureters, that is to say those comprising two or more suction branches, each provided with its sprayer or sprayers and parts for regulating the supply to independent engines or to cylinders or groups of cylinders of one and the same engine.

The invention has for its object to make it possible to arrange apparatus of this kind so as to enable the output of the sprayers in each of the suction branches of the said apparatus to be simultaneously regulated by means of a single control.

The invention consists, in inserting an obturator between the constant level tank and the sprayer or sprayers corresponding to each suction branch, and in providing the said obturators with means for simultaneously actuating them.

The invention comprises certain other arrangements, more explicitly referred to hereinafter.

The invention will be understood from the following description as well as from the accompanying drawing in which:

Figure 1 shows, in section on the line 1—1 of Fig. 2, a portion of the carbureter; Fig. 2 shows the same carbureter in plan, in section on the lines 2—2 and 2⁰—2⁰ of the Fig. 1. Fig. 3 shows the same carbureter in section on the line 3—3 of Fig. 2.

The carbureter is provided with a constant level tank *a*, two suction branches *b*¹ *b*², two sprayers *c*¹ *c*² opening respectively into each of the said branches and both supplied direct from the constant level tank *a*.

The carbureter is built in the usual manner, care being taken to connect each sprayer, to the inner chamber of the constant level tank by means of an independent conduit *e*¹ *e*² provided in the bottom of the said constant level tank.

The ends which open into the inner chamber of the constant level tank *a* are so dimensioned or gaged that, firstly the output of the sprayers is unable to exceed a given value, and that secondly, the output of one of the sprayers is exactly the same as that

of the other sprayer. In the bottom of the constant level tank *a* is provided a bore arranged to extend transversely of the conduits *e*¹ *e*² and to intersect the same, as clearly shown in Fig. 3.

A piston *g* is slidably disposed in the bore *f* and has provided therein two gaged openings *g*¹ *g*² of the same diameter as the gaged portion of the conduits *e*¹, *e*² so that after the piston has been put in place, it is possible to bring the openings *g*¹ *g*² in registering alinement with the conduits *e*¹ and *e*².

The plug *i* is threaded into one end of the bore *f* and a helical spring *h*, arranged in the opposite end of said bore, having one of its ends bearing against a cap or closure for that end of the bore and its opposite end bearing against one end of the piston *g*, serves to normally maintain the other end of said piston against the inner end of the plug *i*, so that the opening *g*¹ and *g*² of the latter will register with the conduits *e*¹ and *e*². A rectangular tongue *g*⁰ projecting from said piston extends into a correspondingly shaped passage *p* in the plug *i*, thus preventing the piston from rotating about its axis and insuring an accurate registering of the openings *g*¹ and *g*² and the conduits *e*¹ and *e*². The plug *i* is further provided with a threaded bore *q* extending as a continuation of the passage *p* and in which is threaded the stem *i*⁰. An operating lever *j* is connected with one of the stems *i*⁰ whereby the latter may be moved longitudinally in the passage *p*, the tongue *g*⁰ being engaged by one end of the stem. Thus it will be readily understood that when the output of the sprayers is too large the amount may be varied by actuating the lever *j* which rotates the stem *i*⁰ so that it will act upon the tongue *g*⁰ of the piston against the action of the spring *h* and shift the piston *g* to close the conduits *e*¹ and *e*² to a desired extent. It is also to be understood that the sprayers *c*¹ and *c*² may be provided with a plurality of sprayer nozzles and also that two or more sprayers could be mounted in each suction pipe. In this way, the considerable advantage is insured that the carbureted mixtures are exactly the same in the two suction branches, and are always regulated simultaneously.

Obviously, the invention is not limited to that method of carrying it out which has been more particularly described, but comprises any modifications.

Having now particularly described and ascertained the nature of my said invention and in what manner the same is to be performed, I declare that what I claim is:—

- 5 1. A carbureter, comprising, a supply chamber, a plurality of sprayers having independent connections with said supply chamber, and an obturator interposed in said connections between the sprayers and said chamber for simultaneously controlling the passage of fluid through said connections, said obturator being provided with a plurality of openings adapted to register with the passages of said connections.
- 10 2. In a carbureter, the combination with the plurality of suction ducts, a supply chamber, a spraying device for each suction duct and having an independent connection with said supply chamber, and an obturator arranged in said connections between said spraying devices and supply chamber for simultaneously controlling the supply fluid to said spraying devices.
- 15 3. A carbureter, comprising, a fluid supply chamber, a plurality of sprayers, a duct connecting each sprayer with the supply chamber, an element having a bore therein extending transversely to said ducts and intersecting the same, an obturator arranged in said bore and having a plurality of pas-

sages therein adapted to register with the passage of the ducts, and means for moving said obturator in said bore whereby the supply of fluid from said supply chamber to said sprayer is simultaneously controlled. 35

4. A carbureter, comprising, a fluid supply chamber, a plurality of sprayers, a duct connecting the sprayers with the supply chamber, an element having a bore therein extending transversely to said duct and intersecting the same, an obturator slidably disposed in said bore and having a plurality of passages therein to normally register with the ducts, a member threaded in said bore and engageable with one end of said obturator to move the latter in the bore for simultaneously controlling the passage of fluid from said supply chamber to said sprayers when said member is rotated, and a spring engaging with the other end of said obturator and to hold the same in engagement with said threaded member and for returning said obturator to its normal position. 40 45 50 55

In testimony whereof I have hereunto set my hand in presence of two subscribing witnesses.

MARC BIRKIGT.
